(57) **CLAIM**

The ornamental design for a display screen or portion thereof with an animated graphical user interface, as shown and described.

DESCRIPTION

FIG. 1 is a front view of a first image in a sequence of a display screen or portion thereof with an animated graphical user interface, showing our new design.

FIG. 2 is a front view of a second image in the sequence. FIG. 3 is a front view of a third image of the sequence; and, FIG. 4 is a front view of a fourth image of the sequence. The appearance of the animated graphical user interface sequentially transitions between the images shown in FIGS. 1 to 4. The process or period in which one image transitions to another forms no part of the claimed design.

The outermost broken line showing a display screen or portion thereof and the broken lines within showing elements of the graphical user interface illustrate portions of the article. The dot-dash broken lines shown throughout the figures illustrate symbolic breaks. The appearance of the article between the dot-dash broken lines forms no part of the claimed design.

1 Claim, 4 Drawing Sheets
